UNITED STATES PATENT OFFICE.

PETER J. PIERETTI, OF MOUNT MORRIS, NEW YORK.

COMMODE.

Application filed June 16, 1927. Serial No. 199,256.

This invention relates to a mechanism for using toilet paper and has for its object the provision of an apparatus for this purpose which performs this function in a manner which is sanitary and avoids possible contagion.

In the accompanying drawings:

Figure 1 is a vertical longitudinal section of a water closet equipped with my invention. Figure 2 is a perspective of the main parts of the apparatus containing my invention. Figure 3 is a bottom plan view of the apparatus, on an enlarged scale. Figures 4, 5, and 6 are fragmentary views, similar to Fig. 3, on a reduced scale, showing different positions of the working parts. Figure 7 is a vertical section, on an enlarged scale, taken on line 7—7, Fig. 5, and showing one position of the mechanism for severing the toilet paper. Figure 8 is a similar view showing the parts in another position. Figures 9, 10 and 11 are fragmentary vertical sections taken on the correspondingly numbered lines in Figs. 5, 4 and 3 respectively. Figure 12 is a fragmentary vertical longitudinal section taken centrally through the apparatus on line 12—12, Fig. 13. Figure 13 is a vertical transverse section taken on line 13—13, Fig. 12.

Similar characters of reference indicate like parts in the several views of the drawings.

The numeral 20 represents the body of a commode, 21 the seat having an opening 22, 23 the pot arranged below said opening, and separated therefrom by a gap 24, and 25 a pocket arranged in the commode in rear of said gap. The apparatus for using toilet paper is mounted on a carriage 26 which is movable back and forth from a position in said pocket to a position in said gap in between the seat opening and said pot and may be guided by longitudinal shoes or runners 27 on the opposite edges of the carriage sliding on rails 28 secured to the body of the commode. Forward and backward movement of the carriage may be effected by a lever 29 pivoted on the body of the commode and having a slot 30 which receives a pin 31 on the carriage.

Upon the central part of this carriage is mounted a wiping wheel or roller which turns about a horizontal transverse axis and has a V-shaped body 32 the summit of whose periphery has a circumferential groove 34,

and whose hubs 35 on opposite ends of the body are provided on their peripheries with inner and outer circumferential grooves 36, 37, respectively.

The wiping wheel is preferably mounted on a wiper shaft 38 journaled in suitable bearings on the carriage and operated by power which is preferably obtained from an electric motor 39 mounted on the rear part of the carriage. Motion at a reduced speed is transmitted from the shaft 40 to the wiper shaft 38 by means consisting preferably of a horizontal counter shaft 41 arranged transversely below the wiping wheel and journaled in a suitable bearing on the carriage, 70 a belt 42 passing around small and large pulleys 43, 44 mounted respectively on the motor shaft and the counter shaft, and a gear pinion 45 arranged on the counter shaft and meshing with a gear wheel 46 on the wiper shaft. The motor is arranged in an electric circuit which includes an electric generator 47 or other suitable electric source and a switch 48 for opening and closing this circuit so as to stop and start the motor.

In front of the lower part of the wiping wheel is arranged a horizontal delivery shaft 49 which is journaled in suitable bearings on the carriage and is provided adjacent to the opposite sides of the lower front part of the wiping wheel with inner and outer delivery wheels 50, 51 each of which has its periphery preferably constructed of polygonal form, as shown in Figs. 2 and 12.

The toilet paper in the form of a web, 90 sheet or strip 53 is supplied from a roll 54 which is mounted on an axle 55 supported on standards 56 rising from the carriage between the motor and the wiping wheel. This strip passes from the roll forwardly 95 under a guide 57 arranged below the wiping wheel, thence upwardly along the front side of the counter shaft 41, thence rearwardly and upwardly around the rear side of the wiping wheel, thence forwardly over the top 100 of this wheel and thence forwardly and downwardly over the front side of the delivery wheels 50, 51. As the strip of paper passes around the wiping wheel the same is drawn tightly against the body and the hubs thereof so that the central part of the strip assumes a V-form in cross section the summit of which is elevated while the edge portions are depressed and clamped against the hubs 105 of the body so as to compel the strip of paper 110

and the wiping wheel to turn forwardly together during the operation of withdrawing paper from the supply roll and moving the V-shaped part thereof past the surface to be cleaned.

As the paper strip passes upwardly in front of the counter shaft and around the rear and top parts of the wiping wheel the longitudinal central part of the strip is engaged on its inner side by a central delivery belt 58 which passes around the groove in the summit of the body and also around a pulley 59 formed by the central part of the delivery shaft 49. As the paper strip passes upwardly in front of the counter shaft 41 each of its edges passes upwardly between the inner side of the feeding-on stretch 60 of a gripping belt and the outer side of the feeding-on stretch 61 of a side guide belt, said feeding-on stretches 60, 61 converging upwardly so that the lower parts of the same are separated, as shown in Fig. 12, and permit the respective edges of the paper strip to pass upwardly between them, while the upper parts of said feeding-on stretches 60, 61 run side by side around the grooves in the respective hubs of the body, and thereby cause the upper gripping turn 62 of the gripping belt to press the paper strip against said hub and the upper turn 63 of the gripping belt to pass around said hub underneath the paper strip between its gripped edge portion and the V-shaped central part, as shown in Fig. 13. By this means a firm hold is obtained on the paper at its edges only which insures positive forward turning of the same with the wiping wheel while the central V-shaped part of the paper strip is elevated above the gripped edges of the same and unobstructed so that no parts of the gripping belts are liable to become soiled while the paper is being moved in engagement with the surfaces to be cleaned, thereby preventing the apparatus from becoming foul or unsanitary.

The lower end of the feeding-on stretch 60 of the gripping belt passes around a pulley 64 formed by the adjacent part of the counter shaft 41 and connects with one end of a rearwardly deflected turn 65 of the gripping belt which passes around a rear guide pulley 66, and the front end of the gripping turn 62 of this belt connects with the upper end of a feeding-off stretch 67 of this belt, the lower end of this feeding-off stretch passing around the front and underside of a front guide pulley 68 and connecting with the other end of the turn 65 of this belt which passes around the rear guide pulley 66. Each of the side guide belts has a front feeding-off stretch 69 extending from the upper turn 63 downwardly and forwardly around the front side of a lower guide roller or pulley 70 formed on the delivery shaft 49 and then passing rearwardly

underneath this pulley and connecting with the lower end of the feeding-on stretch of this belt.

By means of the upper front or feeding-off stretches of the belts, the paper strip, after performing a wiping operation on the upper part of the wiping wheel, is released from the same and delivered forwardly and downwardly therefrom to the delivery rollers or wheels 50, 51 which latter preferably direct the paper to the pot 23 which is arranged below the toilet seat opening.

In order to insure disengagement of the edge of the strip or web of the paper from the gripping and guiding belts after the wiping operation has been performed, stripping means are provided consisting preferably of a plurality of fingers 71 arranged adjacent to the delivery parts of the gripping and guiding belts and delivery wheels 55 and serving to deflect the used part of the paper away from the feeding-off stretches of the belts and thus avoiding clogging of the apparatus with soiled paper.

These stripping fingers and the front and rear guide rollers 68 and pulleys 66 may be mounted in any suitable manner on the adjacent parts of the carriage, as shown in Figs. 1, 2, 3 and 12.

While a person is occupying the seat and using the commode the wiping mechanism is retracted from the gap between the seat and the pot so as to permit unobstructed passage from the seat to the pot and during this time the motor is shut off and rendered inoperative. When, however, the person has finished and is ready for wiping then the electric switch 48 is closed so that the motor will operate the paper actuating mechanism. While the motor is running the carriage is moved from its rearward position in the pocket 25 of the commode, as shown by full lines in Fig. 1, to its forward position in the gap between the seat and the pot, as shown by dotted lines in the same figure, whereby the upper V-shaped part of the wiping wheel not only sweeps the crotch of the person but also rotates in engagement therewith, thereby passing a considerable length of the paper web or strip over the parts to be cleaned and effectively removing any matter therefrom. After this wiping operation the rotation of the wiping wheel is continued for a short time so as to carry the soiled paper downwardly into the pot and leave only fresh or unsoiled paper on the wiping wheel and adjacent parts of the apparatus. After the soiled section has been deposited in the pot the motor is stopped by opening the switch 48 and while the wiping apparatus is still between the seat and the pot the paper web or strip is severed above the soiled part so that the latter drops into the pot. This severing operation is preferably effected automatically

by means which may be constructed as follows:—

The numeral 72 represents the stationary blade of a pair of cutting shears and 73 the movable blade of the same, these blades being pivotally connected by a vertical pin 74 and the stationary blade being secured transversely to the front part of the carriage. While the carriage is being moved forwardly the movable blade is swung rearwardly so as to open the shears and the same remain open while the carriage is between the seat and the pot, thereby permitting the web or sheet of paper to be moved from the wiping wheel downwardly between the blades of the shears and into the pot. As the carriage is moved rearwardly the movable blade is swung across the relatively fixed blade of the shears and thereby severs the web of paper and permits the lower advancing end to drop into the pot. The movable blade is yieldingly held either in its open position or in its closed position by means of a locking lever 75 pivoted on the carriage and having its forwardly projecting free end connected by a link 76 with a tail 77 arranged on the inner end of the movable blade and a tension spring 78 connected at one end with the carriage and connected at its other end by a link 79 with the locking lever. When the shears are closed and the movable blade is swung forwardly the connection between the spring 78 and the locking lever is on the outer side of the pivot of this lever whereby the pull of this spring holds the movable blade shut, as shown by full lines in Fig. 3, at which time the closing movement of the movable blade is limited by a stop 80 on the carriage engaged by the tail of the movable blade. Upon swinging the movable blade open the tension on the spring 78 is increased until the locking lever 75 has been turned in the opposite direction sufficient to bring the connection between the spring 78 and the locking lever on the inner side of the pivot of this lever, and when this occurs the tension of this spring quickly completes the opening movement of the movable blade, the movement of the parts in this direction being limited by a stop 81 on the locking lever engaging the adjacent part of the carriage, as shown by dotted lines in Fig. 3, and by full lines in Fig. 5. The initial part of the turning movement of the movable blade for closing the same is effected during the initial part of the backward movement of the carriage by engagement of a cam 82 on the tail of the movable blade with a stationary trip pin 83 on the adjacent part of the commode, such as one of the rails 28, which cam and pin turn the movable blade far enough to swing the locking lever 75 past its dead center and then the spring 78 completes this closing movement of the movable

blade. The initial part of the opening movement of the movable blade is effected by a shifting lever 84 pivoted on the carriage and having one of its arms connected by a link 85 with the locking lever, and a tappet 86 arranged on the other arm of the shifting lever and adapted to engage a normally stationary trip arm 87 which is pivoted on the adjacent stationary part of the commode and is yieldingly held against a stop 88 thereon by a spring 89 connecting this arm and the commode, as shown in Fig. 4. This trip arm 87 by engagement with the shifting lever 84 turns the latter sufficiently to swing the locking lever past its dead center 85 in the cutter opening direction and thereafter the completion of the closing movement of the movable cutter blade is effected by the tension spring 78.

During the backward movement of the carriage the trip arm 87 must be moved out of the path of the shifting lever 84 so that the latter can swing forwardly freely during the quick closing movement of the movable cutter blade, this being accomplished by a deflecting pin 90 mounted on the carriage and adapted to engage the front side of the trip arm 87, as shown in Figs. 5 and 7, and push the same rearwardly out of the path of the shifting lever so that the latter is free to swing from its rearward position shown in Fig. 5 to its forward position shown in Fig. 6 for closing the shears without interference from the trip arm 87. During the last part of the backward movement of the carriage the shifting lever 84 again deflects the trip arm 87 in order to get behind it and engage therewith, as shown in Fig. 4, during the initial part of the subsequent forward movement of the carriage for again 105 opening the movable cutter blade.

In order to permit the deflecting pin 90 to clear the trip arm 87 during the forward movement of the carriage this pin is provided with an inclined front side 91 which is adapted to engage an inclined rear side 92 on the trip arm 87, as shown in Fig. 8, and thereby depress this pin so as to clear the trip arm. Such depression of the deflecting pin is rendered possible by mounting the same on a guide rod 93 which slides vertically in the bottom of a pocket 94 on the carriage, and a spring 95 which yieldingly holds the deflecting pin in its operative position and bears with its ends against the bottom of 110 this pocket and the underside of said deflecting pin, as shown in Figs. 7 and 8.

During the forward or closing movement of the movable cutter blade the adjacent part of the strip of paper to be cut is pushed forwardly into the crotch of the shears by a push finger 96 arranged on the free end of the shifting lever.

It will be apparent that the operation of cutting the strip of paper is effected auto- 130

matically during the return movement of the wiping mechanism from its forward wiping position to its rearward inactive position and that at no time are the hands of a person required for using the toilet paper after the toilet has been used.

I claim as my invention:—

1. An apparatus of the character described comprising a wiping wheel having a body, the periphery of which is V-shaped in cross section and reduced hubs on opposite sides of the body, and bending and guiding means for holding a strip of paper circumferentially on said wheel so that its central part conforms to the V-shaped part of the body and the edges thereof engage the hubs thereof including belts adapted to pass around the edge portions of the strip which engage said hubs.
  2. An apparatus of the character described comprising a wiping wheel having a body the periphery of which is V-shaped in cross section and reduced hubs on opposite sides of the body, and bending and guiding means for holding a strip of paper circumferentially on said wheel so that its central part conforms to the V-shaped part of the body and the edges thereof engage the hubs thereof including gripping belts adapted to pass around the outer side of the edge portions of the strip which engage said hubs, and delivery belts adapted to pass around said hubs on the inner side of the edge portions of said strip.
  3. An apparatus of the character described comprising a wiping wheel having a body the periphery of which is V-shaped in cross section and reduced hubs on opposite sides of the body, and bending and guiding means for holding a strip of paper circumferentially on said wheel so that its central part conforms to the V-shaped part of the body and the edges thereof engage the hubs thereof including gripping belts adapted to pass around the outer side of the edge portions of the strip which engage said hubs, delivery belts adapted to pass around said hubs on the inner side of the edge portions of said strip, each of said gripping belts having a lower rearwardly extending turn and each of said delivery belts having a lower front turn, and rotating supports for the lower parts of said gripping and delivery belts.
  4. An apparatus of the character described comprising a wiping wheel having a body the periphery of which is V-shaped in cross section and reduced hubs on opposite sides of the body, and bending and guiding means for holding a strip of paper circumferentially on said wheel so that its central part conforms to the V-shaped part of the body and the edges thereof engage the hubs thereof including gripping belts adapted to pass around the outer side of the edge portions of the strip which engage said hubs.
- tions of the strip which engage said hubs, delivery belts adapted to pass around said hubs on the inner side of the edge portions of said strip, each of said gripping belts having a lower rearwardly extending turn 70 and each of said delivery belts having a lower front turn, rotating supports for the lower parts of said gripping and delivery belts, a central delivery belt having an upper rear turn passing around the periphery 75 of said body and a lower front turn, and a rotary support for said last mentioned turn of the central delivery belt.
5. An apparatus of the character described comprising a wiping wheel having a body the periphery of which is V-shaped in cross section and reduced hubs on opposite sides of the body, and bending and guiding means for holding a strip of paper circumferentially on said wheel so that its central part conforms to the V-shaped part of the body and the edges thereof engage the hubs thereof including a central delivery belt having an upper rear turn passing around the periphery of said body and a lower front turn, and a rotary support for said front turn.
  6. An apparatus of the character described comprising a wiping wheel having a body the periphery of which is V-shaped in cross section and reduced hubs on opposite sides of the body, and bending and guiding means for holding a strip of paper circumferentially on said wheel so that its central part conforms to the V-shaped part of the body and the edges thereof engage the hubs thereof including a central delivery belt having an upper rear turn passing around the periphery of said body and a lower front turn, a rotary support for said turn, and delivery wheel rotating with said front support.
  7. An apparatus of the character described comprising a wiping wheel having a body the periphery of which is V-shaped in cross section and reduced hubs on opposite sides of the body, and bending and guiding means for holding a strip of paper circumferentially on said wheel so that its central part conforms to the V-shaped part of the body and the edges thereof engage the hubs thereof including a central delivery belt having an upper rear turn passing around the periphery of said body and a lower front turn, a rotary support for said turn, and delivery wheel rotating with said front support, and each having a polygonal periphery.
  8. An apparatus of the character described comprising a wiping wheel, means for feeding a strip of paper circumferentially around said wheel and removing the same therefrom, and means for severing said strip on the delivery side of said wheel including a relatively stationary cutter blade, a movable cutter blade pivoted to swing 130

relative to said stationary blade, a carriage upon which said wiping wheel and cutter blades are mounted and which is movable toward and from the operative position of said wiping wheel, and means for actuating said movable cutter blade including a locking lever pivoted on the carriage and movable alternately from one side of its dead center to the other, a connection between 5 said locking lever and said movable cutter blade, a spring connected at one end with said carriage and at its other end with said locking lever and adapted to move from one side of the dead center of said lever to the other, and means for alternately rocking 10 said locking lever and said movable cutter blade, a spring connected at one end with said carriage and at its other end with said locking lever and adapted to move from one side of the dead center of said lever to the other, and means for alternately rocking 15 said locking lever in opposite directions.

9. An apparatus of the character described comprising a wiping wheel, means for feeding a strip of paper circumferentially around 20 said wheel and removing the same therefrom, and means for severing said strip on the delivery side of said wheel including a relatively stationary cutter blade, a movable cutter blade pivoted to swing relative to said stationary blade, a carriage upon which said wiping wheel and cutter blades are mounted and which is movable toward and from the operative position of said wiping wheel, and means for actuating said 25 movable cutter blade including a locking lever pivoted on the carriage and movable alternately from one side of its dead center to the other, a connection between said locking lever and said movable cutter blade, a spring connected at one end with said carriage and at its other end with said locking lever and adapted to move from one side of the dead center of said lever to the other, and means for alternately rocking 30 said locking lever in opposite directions, including a shifting lever pivoted on said carriage and connected with said locking lever, and a trip arm mounted on a stationary support and adapted to be engaged by said shifting lever for turning the latter.

10. An apparatus of the character described comprising a wiping wheel, means for feeding a strip of paper circumferentially around said wheel and removing the same therefrom, and means for severing said strip on the delivery side of said wheel including a relatively stationary cutter blade, a movable cutter blade pivoted to swing relative to said stationary blade, a carriage upon which said wiping wheel and cutter blades are mounted and which is movable toward and from the operative position of said wiping wheel, and means for actuating said movable cutter blade including a locking lever pivoted on the carriage and 50

60 locking lever pivoted on the carriage and

movable alternately from one side of its dead center to the other, a connection between said locking lever and said movable cutter blade, a spring connected at one end with said carriage and at its other end with said locking lever and adapted to move from one side of the dead center of said lever to the other, and means for alternately rocking said locking lever in opposite directions, including a shifting lever pivoted on said carriage and connected with said locking lever, a trip arm mounted on a stationary support and adapted to be engaged by said shifting lever for turning the latter, said trip arm being yieldable in one direction 70 and rigid in the opposite direction, and a tappet mounted on said carriage and yieldably engaging one side of said trip arm and rigidly engaging the opposite side of the same.

11. An apparatus of the character described comprising a wiping wheel, means for feeding a strip of paper circumferentially around said wheel and removing the same therefrom, and means for severing said strip on the delivery side of said wheel including a relatively stationary cutter blade, a movable cutter blade pivoted to swing relative to said stationary blade, a carriage upon which said wiping wheel and cutter blades are mounted and which is movable toward and from the operative position of said wiping wheel, and means for actuating said movable cutter blade including a locking lever pivoted on the carriage and 85 movable alternately from one side of its dead center to the other, a connection between said locking lever and said movable cutter blade, a spring connected at one end with said carriage and at its other end with said locking lever and adapted to move from one side of the dead center of said lever to the other, and means for alternately rocking 90 said locking lever in opposite directions, including a shifting lever pivoted on said carriage and connected with said locking lever, and a trip arm mounted on a stationary support and adapted to be engaged by said shifting lever for turning the latter.

12. An apparatus of the character described comprising a wiping wheel, means for feeding a strip of paper circumferentially around said wheel and removing the same therefrom, and means for severing said strip on the delivery side of said wheel including a relatively stationary cutter blade, a movable cutter blade pivoted to swing relative to said stationary blade, a carriage upon which said wiping wheel and cutter blades are mounted and which is movable toward and from the operative position of said wiping wheel, and means for actuating said movable cutter blade including a locking lever pivoted on the carriage and 100

110 locking lever pivoted on the carriage and

PETER J. PIERETTI.
